UNITED STATES PATENT OFFICE.

FRANK M. EDGAR, OF DETROIT, MICHIGAN, ASSIGNOR TO TERNSTEDT MANUFACTURING CO., OF DETROIT, MICHIGAN, A CORPORATION OF MICHIGAN.

DOOR BUMPER.

Application filed January 17, 1924. Serial No. 686,732.

This invention relates to a door bumper and registering device more commonly known to the trade as a dove-tail.

The prior art shows devices of this character which are provided with a keeper socket for the purpose of thrusting against the striker carried by the door in a plane transverse to the plane of the door.

This invention relates to an improvement over the old form of bumper and registering device, in that the keeper socket is constructed in such a way as to thrust against the door in a plane transverse to the plane of the door and also in a plane parallel to the plane of the door. This will prevent the door from rattling or vibrating on its hinges in a line parallel to the plane of the door. The line of thrust transverse to the plane of the door serves the same purpose as in the prior art. The improvement resides in the two-way thrust which thoroughly eliminates all door rattling.

My improved form of striker is well adapted to this form of keeper socket and enables me to form the striker of a stamping, because of the fact that the keeper socket is provided with a two-way taper and from the description it will be seen that this taper in the plane parallel to the plane of the door enables the manufacturer to make the striker of a stamping as the taper enables the stamping to be withdrawn quite readily from the dies.

In the drawings:—

Fig. 1 is a perspective view of a portion of an automobile body showing my improved striker and keeper socket installed therein.

Fig. 2 is a front elevation of the keeper member.

Fig. 3 is a section on the line 3—3 of Fig. 2, showing the striker engaged within the socket.

Fig. 4 is a section on the line 4—4 of Fig. 3, with the striker removed.

Fig. 5 is an elevation of the sheet metal stamping which forms the striker.

The plate *a* has secured on the back thereof by means of screws *b*, a casting *c*. This casting is provided with recesses in which is preferably placed rubber blocks *d*. Wearing or grip plates *e* are fitted on these rubber blocks, the inherent resiliency of the

rubber blocks forcing the grip plates *e* towards each other. As shown in Fig. 2, the plate *a* is cut away as at *f* to expose these grip plates so that the striker *g* carried by the door may engage between the two grip plates, and wedge therein, the yieldable rubber blocks resisting the wedging action.

The grip plates form the side walls of the keeper socket and as shown in the drawings, these walls converge in two directions, to wit,—in a line parallel to the plane of the door and in a line transverse to the plane of the door. This is what I call a two-way taper.

As shown in Fig. 5, the striker plate *g* is made of a stamping; the striker *x* which engages between the grip plates of the keeper socket is in the form of a stamped-out projection, the side walls of said striker converging in a line parallel to the plane of the door, and in a line transverse to the plane of the door. This is what I call a two-way taper which corresponds to the two-way taper of the keeper socket. The taper in a line parallel to the plane of the door is more clearly shown in Fig. 3 and it will be evident from this that the striker may be readily formed of a stamping since this taper provides sufficient draft so that the stamping may be withdrawn from the dies after the struck out striker is formed in the striker plate.

The resilient rubber blocks thrust against the grip plates and consequently the taper in the plane of the door results in a thrust transmitted from the rubber blocks to the door in the plane of the door. Similarly, the rubber blocks thrust against the door in a plane transverse thereto because of the corresponding taper of the socket and striker in a line transverse to the plane of the door.

The advantage of this is quite evident. Upon the closing of the door the striker carried by the door engages within the keeper socket carried by the door post, and the thrust is transmitted from the rubber blocks to the door tending to force the same outwardly or in a line transverse to the plane of the door, thereby thrusting the latch bolt against the side of the lock casing to prevent rattling of the latch bolt. In addi-

tion, the thrust is exerted in a plane parallel to the plane of the door and prevents rattling of the same on the hinges. As a result of this two-way thrust in the door, all rattling is eliminated.

What I claim is:—

1. In a door bumper or dovetail, the combination of a keeper provided with a pair of gripping members converging together in the direction of impact of the striker and diverging outwardly from the door post in the plane of the door opening, the said keeper and the gripping members so arranged to afford the gripping members a yielding action, and a striker member comprising a plate for the mounting of same and a striking portion comprising a projection tapered from end to end and having its walls also converging toward the outside of the projection, the said converging faces of both the gripping members and this projection of the striker being substantially complementary, whereby when the two inter-engage the yielding force of the gripping members serves
- 25 to stress the door both outwardly in its path

of opening and compressively in the plane of the door opening.

2. In a door bumper or dovetail, the combination of a keeper provided with a pair of gripping members and means for yielding backing up the gripping members, the said gripping members having gripping faces which converge in the direction of impact of the striker and diverge from the face of the door post in the plane of the door opening, and a striker provided with a projection and in the form of a stamping in which the projection is formed as a hollow member with tapered walls converging in the direction of the impact and also converging laterally outwardly from the face of the striker to form complementary engaging surfaces for striker and keeper which stress the door outwardly in the direction the door opens and also stresses the door compressively in the plane of the door opening.

In testimony whereof I have affixed my signature.

FRANK M. EDGAR.
